UNITED STATES PATENT OFFICE.

HARRY M. SPAHR, OF SPAHR, MARYLAND.

COMPOSITION FOR THE FUMIGATION TREATMENT OF FOWL.

No Drawing.

Application filed December 21, 1923. Serial No. 681,948.

To all whom it may concern:

Be it known that I, HARRY M. SPAHR, a citizen of the United States, residing at Spaehr, in the county of Frederick and State of Maryland, have invented certain new and useful Compositions for the Fumigation Treatment of Fowl, of which the following is a specification.

The object of my invention is the production of a composition for the fumigation treatment of fowl having roup, colds, canker, catarrh, chicken-pox, and other similar diseases.

My composition consists of a mixture of ground cubeb berries, kiln dried pine needles, kiln dried pine sawdust, pine tar, turpentine, sulphur and coal tar.

In preparing the composition I prefer to use the ingredients in about the following proportions, viz: forty per cent ground cubeb berries, ten per cent kiln dried ground pine needles, five per cent kiln dried pine sawdust, twenty per cent pine tar, fifteen per cent turpentine, five per cent sulphur, and five per cent coal tar.

The ingredients are thoroughly mixed and placed in cans having suitable closures.

In using my composition, the diseased fowl are placed in a building and all windows and doors closed to make same as near air-tight as possible. A sufficient quantity of the composition, say two or three tablespoons full for an average size building, is then placed in an iron pot, or other suitable receptacle, and lighted. The composition is allowed to burn until the smoke becomes dense and the fowl become restless, then

a cover is placed over the composition and removed from the building. Allow the smoke to remain in the building for thirty or forty minutes then open windows and doors. This treatment is repeated as often as necessary. The burning composition produces a vapor or smoke which will loosen the accumulated mucous in the nostrils and eyes, causing a free discharge of mucous, thereby effecting an almost instant relief and greatly assisting nature to effect an absolute cure. The healing and soothing effect of the medicinal properties of said smoke or vapor produced by this composition right on the diseased membranes effect a speedy recovery, for fowls must inhale and breathe and when confined to a closed house are compelled to inhale the vapor or smoke produced by the burning of this composition.

I claim:

1. A composition for the fumigation treatment of fowls, consisting of ground cubeb berries, kiln dried ground pine needles, kiln dried pine sawdust, pine tar, turpentine, sulphur and coal tar, substantially as described.

2. A composition for the fumigation treatment of fowls, consisting of forty per cent ground cubeb berries, ten per cent kiln dried ground pine needles, five per cent kiln dried pine sawdust, twenty per cent pine tar, fifteen per cent turpentine, five per cent sulphur and five per cent coal tar.

In testimony whereof I affix my signature.

HARRY M. SPAHR.
